MOULD

Edward Bevan Ratcliffe, Hamilton, Ontario, Canada, assignor to Angelstone Limited, Hamilton, Ontario, Canada

Application April 24, 1956, Serial No. 580,234

2. Claims. (Cl. 25—119)

This invention relates to moulds, and more particularly to moulds for poured concrete or cast stone bricks and blocks.

Concrete blocks and so-called "cast stone" blocks have attained universal consumer acceptance. These blocks are formed by charging a mix of cement, aggregate (which in the case of "cast stone" will include various types of crushed stones) and water into shaped moulds, which, for economy and quality manufacture may consist of a compartmented tray. These moulds may then be vibrated to pack the mix and provide a dense product, and then permitted to set with or without curing.

Because for some of the larger shapes these blocks may weigh several hundred pounds, the blocks are often difficult to remove from the mould after setting.

Various methods of obtaining quick and easy removal of these moulds have been suggested. For instance, it is common to make the dividers between the various compartments in the mould removable. In such a case, the ends of the mould are removed and the dividers withdrawn, one at a time. After all the dividers have been removed, the blocks may be withdrawn again one at a time to prevent damage to the blocks.

This method, now in extensive use is not only time consuming, and consequently expensive, but in addition severely limits the size and quantity of the blocks which may be produced in a single mould.

In addition, blocks are often required with a simple groove or other undercut portion precisely located therein. For example, a block used as the base of a window should have a longitudinal groove on the underside of the block to prevent water from running along the underside of the block and into the structure of the building. Such a groove acts as a drip and draws water off before it reaches the structure. Such grooves, if cut by hand, are expensive and time consuming.

It is an important object of this invention, therefore, to provide a mould for poured concrete or cast stone bricks and blocks which will permit of easy removal of the set bricks and blocks.

It is another object of this invention to provide such a mould as will obviate individual handling of the set bricks and blocks to effect removal from the mould.

It is a further object of this invention to provide such a mould of greater capacity as to size of block and/or number of blocks than has heretofore been practical.

It is still a further object of this invention to provide such a mould whereby a groove or other simple undercut portion may be provided in the finished block without the necessity of hand cutting.

These and other advantageous objects will become apparent through a consideration of the following detailed description, taken in conjunction with the attached drawings in which:

Figure 1 is a perspective view showing an assembled mould with ends removed constructed so as to embody features of this invention.

2

Figure 2 is an end view of the mould shown in Figure 1 showing the mould in position for filling.

Figure 3 is a view similar to Figure 2 but showing the mould in position for emptying.

5 Figure 4 is an end view of a mould liner, and

Figure 5 is a view similar to Figure 2 but showing the mould liner in position.

The invention consists broadly in the formation of a multi-compartment mould from a number of stock steel 10 channels, joined at their sides to provide a unitary structure whereby, after blocks poured therein have set, the mould may be inverted and the bottom flexed distending the sides of each compartment, and permitting the blocks to drop out of the mould without the necessity of individual handling. A further embodiment of the invention also contemplates the use of a mould liner having such a configuration as to provide a groove or other simple undercut portion on the finished block with the blocks when the mould is flexed about its bottom, and which may thereafter easily be withdrawn from the blocks.

In greater detail, and referring to the drawings, Figure 1 illustrates in perspective a completely assembled mould constructed so as to embody features of this invention. The mould has two removable ends 1 and 2 which may be releasably connected to the body of the mould 3 as by means of bolts, brackets and eyes indicated generally as at 4. The ends 1 and 2 may conveniently be formed with an I-shaped cross section of the proper dimensions so that one side of the I fits snugly over the ends of the channels 3A, 3B, etc. An end closure of this shape affords the following advantages:

(a) It serves as a guide to locate the end properly on the form;

(b) It holds the form rigid when the form is being carried and when the form is inverted, it prevents the form from flexing in the manner hereinafter described (i.e. stones cannot be removed until the ends are removed); and

(c) It affords the necessary rigidity to the complete form assembly.

40 The body of the mould 3 is shown in end view in Figure 2, the ends 1 and 2 having been removed for purposes of this illustration and will be seen to comprise a plurality of stock steel channels 3A, 3B, 3C, etc. firmly joined together by their sides to form a unitary structure consisting of a number of longitudinal channels. The stock channels may conveniently be joined together by means of a series of spot welds along the top edge and end edges thereof. The outside channels are reinforced with a single plate which may be similarly affixed.

50 The use of such channels in the manner described gives walls between the channels of double metal thickness, and a bottom of single metal thickness. This feature is particularly important as will be pointed out hereinafter.

The longitudinal channels may, if desired, be separated 55 into two or more compartments by the use of transverse dividers 5. For reasons which will become apparent hereinafter, these dividers must be carefully shaped so as to conform closely with the configuration of the channel, and must be secured in the channel through fastening only 60 on the bottom thereof. This could be accomplished by a simple fillet weld.

Handles 6 are provided on both sides of the body of the mould 3.

65 The width and depth of the channels will determine the cross sectional dimensions of the cast block while the number and location of the transverse dividers will determine the length. These will, of course, be chosen to produce a block of whatever dimensions are required.

70 The number of channels and the length thereof will be governed solely by structural considerations bearing in mind the weight of the finished block.

In the cast stone art, two standard and desirable blocks are $2\frac{3}{8}$ " x 4" in cross section and either 2 feet or 4 feet in length. Both of these standard sizes can be produced in a finished mould approximately 4' x 4'. Such a mould would be formed from 18 channels, each 4' long and having an inside width of $2\frac{3}{8}$ " and an inside depth of at least 4". The 2' blocks would be formed by the provision of one set of transverse dividers located midway along the channels.

The operation of a mould so constructed is as follows: With the ends secured in place, the mould is charged with mixed cement, aggregate, and water of the desired composition. To obtain a more dense and uniform product, the mould may then be transferred to a vibrating table where it is agitated to effect a packing of the particles. The mould is then removed and the blocks allowed to set with or without curing as for instance, by means of steam treatment.

After the blocks have set, the mould is inverted and the ends 2 of the mould body 3 are removed. Handling may be effected through the use of a revolving carriage lift truck which engages the handles 6 provided in the sides of the mould body 3.

After the mould is so inverted, the weight of the blocks will cause the base to flex (as shown in exaggerated form in Figure 3) and the sides will distend, permitting the blocks to drop out of the mould.

It is important that the mould in order to permit this quick removal possess at least two structural qualities.

First, the bottom must be flexible to permit the side walls to distend, and second, the side walls between the channels must be rigid in order to withstand deformation from the weight of the mix charged therein and thus provide a uniform block in spite of repeated prolonged use.

These two features are accomplished in my invention through the building up of the mould through the joining of a number of channels. Formed in such a way, the bottom is of single metal thickness, permitting of flexibility, while intermediate walls are of double metal thickness, affording rigidity and strength. In addition, the flexibility of the bottom is measured by the fact that it comprises a plurality of joined compartments rather than a single unitary surface.

For the 4' x 4' forms and channel dimensions of 4" x $2\frac{3}{8}$ " a 16 gauge steel will be found to give the required flexibility.

A further embodiment of the invention is illustrated in Figure 4. In many applications, it may be desirable, for ornamental or structural reasons, to provide a groove or other undercut portion on the finished block. Blocks of this type are in extensive use as window sills, and a longitudinal groove on the underside of such a sill will prevent dripping water from running along the underside of the block and into the structure of the building.

To produce such a groove, it is necessary to provide a ridge on the form. Such a ridge could be formed in-

tegrally on one side wall of each mould compartment, but if this were done, it might preclude the set block from dropping out of the mould, since the bottom of the mould would require extensive flexing to provide the relatively great separation of the dividers to permit the ridge to be withdrawn from the groove. In practice to provide a groove of the required dimensions, the bottom cannot be flexed sufficiently to permit the block to drop out without using extremely light metal which would not give sufficient durability to the form.

This disadvantage is obviated through the use of a mould liner indicated at 7 in Figure 4. This liner formed of flexible metal, fits over the compartment side walls and lines the bottom of all compartments. When the mould is inverted and flexed, the liner drops out with the blocks, and may readily be withdrawn therefrom. The liner, of course, is formed to incorporate a ridge of the required dimensions to provide the groove or undercut portion required on the finished block.

In the preferred embodiment described above, a liner of 20 gauge steel would possess the required properties.

The invention has been described in detail with reference to preferred embodiments. It is to be understood, however, that such embodiments are offered by way of illustration only, and are not intended to be limitations of the invention. Such embodiments of the invention as come within the scope and purview of the appended claims, are to be considered as part of this invention.

What I claim as my invention is:

1. A multi-compartment concrete and cast stone block mould comprising a plurality of channels firmly joined together at their sides providing thereby a unitary structure, the properties and dimensions of the channels being such as to provide thereby a flexible bottom for said unitary structure, a plurality of transverse dividers located in said channels said dividers being of such dimensions as to fit firmly in the channels and being affixed to the channels only at the bottom thereof, and removable end members adapted to seal the ends of said unitary structure.

2. A multi-compartment mould as claimed in claim 1 together with a flexible removable mould liner, said liner being adapted to line the sides and bottoms of each of said channels, and having a ridge of defined dimensions formed therein adapted to provide a groove of corresponding dimensions in the cast blocks.
